UNITED STATES PATENT OFFICE.

LOUIS SCHLESINGER, OF MILWAUKEE, WISCONSIN.

PRINTING APPARATUS.

No. 830,617.

Specification of Letters Patent.

Patented Sept. 11, 1906.

Application filed February 1, 1904. Serial No. 191,410.

To all whom it may concern:

Be it known that I, LOUIS SCHLESINGER, a citizen of the United States, and a resident of Milwaukee, county of Milwaukee, and State 5 of Wisconsin, have invented certain new and useful Improvements in Printing Apparatus, of which the following is declared to be a full, clear, and exact description.

The invention relates to a printing apparatus and seeks to provide a simple and effective device by which menu-cards and the like may be rapidly printed by hand without requiring special skill on the part of the operator.

15 The invention consists in the features of construction, arrangements, and combinations of parts hereinafter set forth, illustrated in the accompanying drawings, and more particularly pointed out in the appended 20 claims.

The improved apparatus comprises a bed, which is preferably stationary, and a carriage, which is preferably arranged to slide upon said bed. Impression and inking rolls are 25 carried by the carriage and so arranged that either one may be thrown into operative relation with the printing-surface on the bed.

In the drawings, Figure 1 is a sectional elevation of the improved printing apparatus. 30 Fig. 2 is a plan view of the bed and connected parts, with the sides of the carriage shown in section. Fig. 3 is a cross-section through the bed and carriage, showing the inking-roll in operation. Fig. 4 is a similar view looking 35 in the opposite direction, showing the impression-roll in operation. Fig. 5 is a detail section on line 5 5 of Fig. 4. Fig. 6 is a detail section on line 6 6 of Fig. 1.

The bed of the apparatus comprises side 40 bars 10, connected by cross-bars 11, 12, and 13, preferably cast in piece with the side bars, and is sustained upon suitable cushioned feet 14. The sliding carriage 15 comprises the side pieces 16 and the connecting cross-bars 45 17 and 18, which are preferably cast in piece with the side pieces. Laterally-projecting V-shaped rails 19 (see Figs. 3 and 4) are secured to the lower ends of the sides 16 of the carriage and are arranged to engage V-shaped grooves 20, formed in the outer faces 50 and near the upper end of the side bars 10 of the bed. By this arrangement the carriage is free to slide back and forth upon the bed, but is rigidly held against vertical play upon

the bed. Stop-bars 21 and 22 are secured to 55 the ends of the slides 10 of the bed and project laterally beyond the same, so as to engage the carriage, limit its to-and-fro movement, and prevent its accidental removal from the bed.

An impression-roll 23 and an inking-roll 24 are mounted on the carriage, and a suitable shifter is provided, whereby as the carriage reciprocates either roll may be thrown into and the other roll out of operative relation with the printing-surface upon the bed. 60 The impression and inking rolls are journaled directly upon the shifter or shifting support, and the latter preferably comprises L-shaped side pieces 25, pivotally connected by bolts 26 to the sides 16 of the carriage and between the cross-bars 17 and 18 thereof. The side pieces 25 of the shifting support are connected by a cross-piece 27, preferably cast in piece therewith, and are also connected at 65 their upper ends above the pivots 26 by a handle 28.

The impression-roll 23 may be of any suitable construction, but is preferably provided with a rubber cover. This impression-roll is 70 mounted upon a shaft 29, journaled between the L-shaped side pieces 25 of the shifting support at one end of the lower portion thereof. At the other end of the lower portions of the L-shaped side pieces is journaled the supporting-shaft 30 of the inking-roll 24, which is formed of any suitable composition. The inking-roll is preferably removably mounted, so that it may be changed or renewed when necessary. For this purpose the ends of its 75 inking-roll shaft 30 are set within open slots 31 in the lower projecting ends of the side pieces 25. Locking-hooks 32 are pivoted to the side pieces 25 of the shifting support and are provided with open-ended slots 33, arranged 80 to engage the projecting ends of the shaft 30. The shaft 30 fits snugly within the slots 31 and 33, which are arranged at an angle to each other, so that the inking-roll is removably but securely held in position.

It will be observed that the impression and inking rolls are so mounted upon the swinging support as to be vertically movable to and from the bed or printing-surface thereon, and also that these rolls are so arranged relatively to the pivots 26 of the swinging support, so that as the latter is shifted in one or the other direction either of said rolls may be

thrown into and the other out of operative relation with the printing-surface on the bed. Stop-lugs 34 are fixed to or formed in piece with the sides 16 of the carriage and engage the sides 25 of the swinging support to limit the movement of the support and the rolls carried thereby in one direction. The lower ends of the swinging supports are arranged to engage stop-surfaces 35 on the cross-bar of the carriage to limit the movement of the support and rolls in the opposite direction.

The printing surface or form may be arranged upon the bed in any suitable manner; but preferably the sides 10 and cross-bars 11 and 12 form a receptacle intermediate the ends of the bed, in which is mounted a removable chase. A ledge 36 is formed around the lower edges of the side and cross bars 10, 11, and 12 within the chase-holding receptacle, upon which the chase rests.

The chase comprises side and end bars 37 and 38 and a bottom plate 39. The end bars 38 are provided with laterally-projecting pins 40, arranged to engage slots 41 in cross-bars 11 and 12, and one of the end bars is preferably provided with an overhanging lip 42 to aid in lifting the chase from the bed of the press. Impression-screws 43 are threaded through the chase at each corner thereof. The lower headed ends of these screws rest upon the ledge 36 at the bottom of the chase-holding receptacle, and their upper ends are slotted, so that they may be readily adjusted by the screw-driver or like implement. By means of these screws the chase, together with the type-form thereon, can be accurately set in a plane parallel to the travel of the impression and inking roll and can be raised and lowered to compensate for variations in the thickness of cards or sheets to be printed. When the screws 43 have been set to so adjust the chase with reference to the path of travel of the impression-roll as to give accurate impression, the chase may be securely held in adjusted position by lock-nuts 44, threaded upon the upper ends of the screws.

A spring-actuated sheet-lifter is provided for normally holding the card or sheet to be printed above the printing-surface or form in the chase, and such sheet-lifter is preferably mounted directly upon the chase to be removable to and from the press therewith. As shown, the sheet-lifter comprises side bars or rails 45 and cross-bars 46 and 47. The side bars 45 are provided with inwardly-projecting ledges 48, upon which the side edges of the card or sheet to be printed are sustained. In the preferred construction side bars 45 are provided at each end with downwardly-projecting pins 49, arranged to slide through openings formed in lugs 50, which project laterally from the sides 37 of the chase. The side bars are also guided in open-

ended slots 51, formed in laterally-projecting portions of the end bars 38 of the chase. As most clearly shown in Fig. 3, washers 52 are mounted to slide upon the pins 49 and are arranged to engage the laterally-projecting lugs 50 on the sides of the chase. Springs 53 are coiled about the pins 49 and are interposed between the washers 52 and the side bars 45, so that the latter are yieldingly supported in position. It will be observed that the sheet-lifting side bars 45 are readily removable from position, and when so removed the lower headed ends of the pins 49 hold the washers 52 and springs 53 upon the pins. In this manner a single sheet-lifter may be employed with a number of different chases. 80

Preferably the cross-bars 46 and 47 are adjustable, so as to properly support sheets and cards of different sizes, and for this purpose the side bars 45 are provided with a series of openings 54, (see Fig. 1,) into which cross-bars 46 and 47 may be adjustably inserted. To permit the ready adjustment of the cross-bars when the side bars 45 are in position upon the chase, these cross-bars are preferably formed of spring metal. As shown, 90 cross-bar 46 is formed of spring-wire, while the cross-bar 47 is preferably flat and formed of resilient sheet metal. An upwardly and laterally turned lip 55 upon the cross-bar 47 forms an adjustable stop or gage, so that the 95 card or sheet to be printed may be accurately placed in position with reference to the form in the chase. The ledges 48 upon the side bars 45 are provided between the cross-bars with upwardly-extended portions 55^a to properly support the central part of the card or sheet to be printed. 100

The ends of the impression cylinder or roll 23 (see Fig. 4) are arranged to engage the side bars or rails 45 to depress the sheet-lifter, so that the card or sheet to be printed may be forced by the roll against the type. (Indicated by dotted lines in Fig. 4.) When the impression roll or cylinder has passed the side rails 45, the spring 43 will raise the sheet-lifter and move the card or sheet up from the surface of the type-form. The inking-roll is also arranged to depress the sheet-lifter, so that the cross-bars 46 and 47 may not be smeared with ink. For this purpose the shaft 30 of the ink-roll 24 is preferably provided with metal wheels 56, spaced apart from the body of the roll and arranged to engage the side rails 45 of the sheet-lifter, as indicated in Fig. 3. 120

At one end of the bed beyond the chase-receptacle is mounted a horizontal rotatable inking-table 57. As shown in Fig. 1, this inking-roll is mounted to rotate upon a spindle 58, projecting upwardly from the cross-bar 13 of the bed or frame of the press. The hub 59 upon the under side of the inking-roll is provided with ratchet-teeth 60, (see Fig.

6.) and a swinging lever 61 is pivoted between its ends upon the bed at one side of the ratchet. The outer end of the lever 61 projects through an opening 62 in the side bar 10 of the bed, and the lever is normally held in the position shown in Fig. 6 by a spring 63, extending between the inner end thereof and the cross-bar 12. Spring-actuated pawls 64 and 65 are arranged to slide longitudinally in sockets in the opposite ends of the lever 61 and are held against lateral twist by means of pins 66, which engage longitudinal slots 67, formed in the ends of the lever. A lug 68 upon the carriage is arranged to engage the pawl 64 upon the outer end of the lever 61 as the carriage is reciprocated. Lug 68 and pawl 64 are so beveled that as the carriage is moved to the right pawl 64 will be shifted inwardly without moving the lever 61. As the carriage moves toward the left the lug 68 will engage pawl 64 and swing the lever 61 against the tension of its spring 63. The lug 65 and the ratchet-teeth 60 are, however, so beveled that during this movement pawl 65 is shifted inwardly against the tension of its spring and moves over the ratchet-teeth 60. As soon, however, as the lug 68 releases the pawl 64 the spring 63 will quickly return the lever 61, and the pawl 65 will positively engage the ratchet-teeth 60 and spin the inking-table through a considerable arc. By thus spinning the inking-table through indeterminate distances the ink will be more evenly distributed thereon than if an ordinary ratchet mechanism were employed for feeding the table intermittently through short regular arcs.

In operation the handle 28 of the shifting support on the carriage is conveniently employed to slide the carriage upon the bed and also to hold the inking-roll in position to receive ink from the table and ink the type during the movement of the carriage in one direction and to hold the cylinder or roll 23 in position to make the impression during the movement of the carriage in the opposite direction. The transverse handle 28 is so arranged that with one hand the operator may conveniently grasp the handle and cross-bar 17 of the carriage to securely hold the impression-roll 23 in lowermost position, (see full lines in Fig. 1,) or the operator may with one hand grasp the handle and cross-bar 18 of the carriage to hold the inking-roll in lowermost position, as indicated in dotted lines in Fig. 1. The stops 34 and 35 for limiting the shift of the swinging support and for limiting the movement of the impression and inking rolls to and from the bed and printing-surface thereon are so arranged that the inking-roll 24 is moved slightly nearer the bed when in lowermost position than is the impression-roll 23 when the latter is in lowermost position. By this arrangement

the roll 24 may properly receive ink from the table 57; but the impression-roll 23 cannot be smeared by the ink on the table. The stops 34 are, however, so arranged as to prevent excessive depression of the inking-roll 24. The lowermost positions of the impression and inking rolls are shown in full and dotted lines in Fig. 1.

The stops 35, preferably so located that when the impression-roll 23 is in lowermost position it will be in or almost in vertical alignment below the pivots 26 of the shifting support, so that such roll will be held firmly in position to make a proper impression, and the operator is not required to exert an undue amount of pressure upon the handle in order to hold the impression-cylinder properly in its work. Moreover, by holding the shifter against the stops 35 during the impression movement of the carriage the impression-rolls will be brought to bear with the even uniform pressure necessary to make the proper imprint. It is thus only necessary that the operator should hold the shifter against the stops 35 during the impression-strokes in order to accomplish uniform printing. The shifting support whereon the impression and inking rolls are journaled is so balanced that, as indicated in Fig. 1, the inking-roll 24 is normally in uppermost position, so that the inking-roll is always removed from the inking-plate when the press is not in operation. This is a valuable feature, since if the inking-roll is left resting upon the ink-plate it will become flattened and unfit for use.

It is obvious that numerous changes may be made in the details of structure without departure from the essentials of the invention and that parts of the improved device may be used without its adoption in entirety.

Having described my invention, what I claim as new, and desire to secure by Letters Patent, is—

1. In printing mechanism, the combination of a bed, of a carriage mounted to slide on said bed, means holding said carriage against vertical movement relative to said bed, an impression-roll and an inking-roll mounted on said carriage, said rolls being shiftable together on said carriage to move either roll into and the other out of operative relation with the printing-surface on said bed, said carriage having stop devices for limiting the movement of said rolls and for properly positioning the same with reference to the printing-surface on said bed, substantially as described.

2. In a printing apparatus, the combination of a bed, a carriage mounted to slide on said bed, means holding said carriage against vertical movement on said bed, an impression-roll and an inking-roll on said carriage, each of said rolls being bodily movable to

and from said bed and an operating-handle on said carriage arranged to simultaneously shift said rolls to throw one into and the other out of operative relation with the printing-surface on said bed, said carriage having stop devices for limiting the movement of said rolls, substantially as described.

3. In a printing apparatus, the combination of a bed, a carriage mounted to slide on said bed, means for holding said carriage against vertical movement on said bed, an impression-roll and an inking-roll on said carriage and each bodily movable to and from said bed, an operating-handle on said carriage arranged to simultaneously shift said rolls to throw one into and the other out of operative relation with the printing-surface on said bed and stops on said carriage for limiting the movement of said rolls and for properly positioning the same with reference to the printing-surface on said bed, substantially as described.

4. In a printing apparatus, the combination of a bed, a sliding carriage thereon, laterally-projecting rails on the sides of one of said parts interlocking with guide-grooves on the sides of the other of said parts to hold said carriage against vertical movement on said bed, an impression-roll and an inking-roll on said carriage, each bodily movable to and from said bed and a shifter on said carriage arranged to simultaneously move said rolls to throw one into and the other out of operative relation with the printing-surface on said bed, said shifter having a handle for operating the same and for sliding said carriage and said carriage having stops for limiting the movement of said rolls and for properly positioning the same relatively to the printing-surface on said bed, substantially as described.

5. In a printing apparatus, the combination of a bed, a sliding carriage on said bed, means for holding said carriage against vertical movement on said bed, an impression and an inking roll on said carriage, each bodily movable to and from said bed and a manually-operable shifter pivoted on said carriage for simultaneously moving said rolls to throw one into and the other out of operative relation with the printing-surface on said bed, said carriage having stops for limiting the movement of said shifter and for positively positioning said rolls in proper relation with the printing-surface on said bed, substantially as described.

6. In a printing apparatus, the combination of a bed, a sliding carriage thereon, means holding said carriage against vertical movement on said bed, a manually-operable shifter pivoted on said carriage, an impression-roll and an inking-roll journaled on said shifter and simultaneously moved thereby to throw one of said rolls into and the other out of

operative relation with the printing-surface on said bed, said carriage having stop devices for limiting the movement of said rolls and for properly positioning the same with reference to the printing-surface on said bed, substantially as described.

7. In a printing apparatus, the combination of a bed, of a sliding carriage thereon, said parts having interlocking guide grooves and rails for holding said carriage against vertical movement on said bed, a manually-operable support comprising connected side pieces and pivoted intermediate its upper and lower ends to said carriage, an impression-roll and an inking-roll journaled in the sides of said support below its pivot, an operating-handle extending between the sides of said support above its pivot and stops on said carriage for limiting the movement of said shifter in opposite directions to properly position said rolls relatively to the printing-surface on said bed, substantially as described.

8. In a printing apparatus, the combination of a bed, a sliding carriage thereon, laterally off-set rails on one of said parts interlocking with guide-grooves in the other of said parts and arranged to hold said carriage against vertical movement on said bed, a shiftable support comprising connected side pieces pivotally mounted on said carriage, an inking-roll and an impression-roll journaled in the sides of said support and arranged to be shifted thereby to throw one of said rolls into and the other out of operative relation with the printing-surface on said bed, said shifter having an operating-handle and said carriage having stops for limiting the movement of the shifter in opposite directions to properly position the rolls with reference to the printing-surface on said bed, substantially as described.

9. In a printing apparatus, the combination of a bed, a sliding carriage thereon comprising sides and connecting cross-bars, laterally-opposite rails on one of said parts engaging guide-grooves in the other of said parts to hold said carriage against vertical movement on said bed, a shifting support comprising connected side pieces pivoted to the sides of said carriage between the cross-bars thereof, an impression-roll and an inking-roll journaled in the sides of said support below its pivot and a handle extending transversely between the sides of said support immediately above its pivot, said carriage having stop devices for limiting the movement of said shifting support, substantially as described.

10. In a printing apparatus, the combination of a bed, a sliding carriage thereon, interlocking guide-grooves and rails between said parts arranged to prevent the vertical movement of said carriage relatively to said bed, a manually-shiftable support compris-

ing connected L-shaped side pieces pivotally mounted on said carriage, an impression-roll journaled to said support at the angles of said L-shaped side pieces below the pivots thereof, a printing-roll journaled to the ends of the lower offset portions of said L-shaped side pieces, said rolls being simultaneously moved by said shifting support to throw one into and the other out of operative relation with the printing-surface on said bed and stops on said carriage for limiting the movement of said shifting support in opposite directions to properly position the rolls with reference to said bed, substantially as described.

11. A printing apparatus comprising a bed, a sliding carriage thereon, means holding said carriage against vertical movement on said bed, an inking-table at one end of said bed, impression and inking rolls movably mounted on said carriage, a manually-operable shifter for throwing either of said rolls into and the other out of operative relation with the printing-surface on said bed, and a stop on said carriage to limit the movement of said impression-roll toward said bed and prevent it from engaging said inking-table.

12. A printing apparatus comprising a bed, a sliding carriage thereon, interlocking devices on said parts for holding said carriage against vertical movement on said bed, an inking-table at one end of the bed, impression and inking rolls carried by said carriage, said rolls being connected together and alternately movable bodily to and from said bed, a manually-operable shifter for throwing either of said rolls into and the other out of operative relation with the printing-surface on said bed, and stops on said carriage for differentially limiting the movement of said rolls and for properly positioning the same relatively to said bed, said stops being arranged to permit a slightly greater extent of depression to said inking-roll than to said impression-roll.

13. A printing apparatus comprising a bed, a sliding carriage thereon, an ink-table at one end of said bed, impression and inking rolls on said carriage, said rolls being connected together and alternately and bodily movable to and from said bed, and means normally holding said inking-roller away from said bed and ink-table.

14. A printing apparatus comprising a bed, a sliding carriage thereon, an ink-table at one end of said bed, a pivoted support on said carriage, impression and inking rolls connected to said support, said support being so arranged that in idle position said inking-roll is always held away from said bed and said ink-table.

15. A printing apparatus comprising a bed, a spring-actuated sheet-lifter for normally holding the sheet to be printed above the

printing-surface on said bed, inking and impression rolls, said rolls being alternately and bodily movable to and from the printing-surface, each of said rolls being arranged to engage and depress said sheet-lifter.

16. In a printing apparatus, the combination with a bed, of a sheet-lifter comprising spring-supported side bars and connecting cross-bars and an inking-roll arranged to engage said side bars to depress said sheet-lifter out of the path of movement thereof.

17. In a printing apparatus, the combination with a bed, of a sheet-lifter comprising spring-supported side bars and connecting cross-bars, an inking-roll and wheels on the shaft of said inking-roll spaced apart from the body of the roll arranged to engage said side bars and depress the sheet-lifter.

18. A printing apparatus comprising a bed, a sliding carriage thereon, impression and inking rolls on said carriage, said rolls being alternately and bodily movable to and from said bed, a shifter arranged to throw either roll into and the other out of operative relation with the printing-surface on said bed and a spring-actuated sheet-lifter for holding the sheet normally above the printing-surface arranged to be engaged and depressed by either of said rolls.

19. In a printing apparatus, the combination with the bed, of a chase removably mounted thereon and sheet-lifting side bars mounted on said chase and freely removable therefrom, said side bars being provided with downwardly-projecting pins fixed thereto and engaging guide-openings in said chase, said pins being freely removable from said openings to permit the free removal of said sheet-lifting side bars and said side bars having supporting-springs fixed thereto and engaging said chase, substantially as described.

20. In a printing apparatus, the combination with a bed, of a chase removably mounted thereon, sheet-lifting side bars mounted on said chase and freely removable therefrom, said side bars being provided with downwardly-projecting pins fixed thereto and fitted within guide-openings in said chase, said pins being freely removable from said guide-openings to permit the free removal of said sheet-lifting side bars, supporting-springs for said side bars coiled about said pins and arranged to engage the edges of said guide-openings and means for holding said springs upon said pins, whereby said springs will not be displaced upon the removal of said side bars from the chase, substantially as described.

21. In a printing apparatus, the combination of a bed, a sliding carriage thereon, means for holding said carriage against vertical movement on said bed, a manually-operable shifter pivoted on said carriage, an impression-roll journaled on said shifter, said

shifter having an operating-handle for throwing said impression-roll into and out of operative relation with the printing-surface on said bed and for reciprocating said carriage 5 and a stop on said carriage for limiting the movement of said shifter and for properly positioning said impression-roll relatively to

the printing-surface on said bed, substantially as described.
